US0D1110325S

(12) **United States Design Patent** (10) **Patent No.:** **US D1,110,325 S**
(45) **Date of Patent:** ** **Jan. 27, 2026**

(54) **COMPONENT FOR AN ELECTRONIC DEVICE**

(71) Applicant: **Apple Inc.**, Cupertino, CA (US)

(72) Inventors: **Jody Akana**, Los Altos Hills, CA (US); **Molly Anderson**, San Francisco, CA (US); **Bartley K. Andre**, Los Gatos, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, Lake Forest, IL (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Sung-Ho Tan**, Vienna (AT); **Clement Tissandier**, San Francisco, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/969,598**

(22) Filed: **Oct. 23, 2024**

Related U.S. Application Data

(63) Continuation of application No. 29/880,352, filed on Jul. 21, 2023, now Pat. No. Des. 1,049,115, which is

(57) **CLAIM**

The ornamental design for a component for an electronic device as shown and described.

DESCRIPTION

FIG. 1 is a top front perspective view of a component for an electronic device showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

(Continued)

FIG. 7 is a top view thereof; and,
FIG. 8 is a bottom view thereof.

The broken lines in the figures show portions of the component for an electronic device that form no part of the claimed design.

1 Claim, 4 Drawing Sheets

Related U.S. Application Data

a continuation of application No. 29/832,406, filed on Mar. 28, 2022, now Pat. No. Des. 997,173, which is a continuation of application No. 29/725,898, filed on Feb. 27, 2020, now Pat. No. Des. 947,848.
